METHOD OF MAKING CARTRIDGE CASES

Robert H. Wallace, Lakewood, and Alex W. Knudsen, Rocky River, Ohio, assignors to The Midland Steel Products Company, Cleveland, Ohio, a corporation of Ohio

Application June 14, 1941, Serial No. 398,174

3 Claims. (Cl. 29—148.2)

1

This invention relates to new and useful improvements in the method of making two piece cartridge cases.

An important object of the invention is to provide method and means for press fitting, squeezing and upsetting the parts of the case together to form a double seal to effectively withstand high gas and hydrostatic pressures.

Another important object of the invention is to provide a cartridge case made of two simple parts to replace the more expensive one-piece drawn cases, which two parts are most effectively locked together with a new method of manufacture.

Other objects and advantages will become apparent during the course of the following description.

In the accompanying drawings forming a part of the description and wherein like parts are designated with like numerals throughout the several views,

Fig. 1 is a longitudinal section through the improved cartridge case showing the same as it takes its assembling position between dies.

Fig. 2 is a similar view showing an intermediate step in the method of connecting the case with the base.

Fig. 3 is another similar view showing the final step in the method, illustrating the final assembled condition of the parts.

Fig. 4 is an enlarged fragmentary section of the case and dies of Fig. 1.

Fig. 5 is an enlarged and magnified section of the case and dies as shown in Fig. 3, illustrating the final form of the joint between the case and the base.

Referring now more in detail to the accompanying drawings and to Figs. 1 and 4, wherein for the purpose of illustration is shown a 105 millimeter cartridge case, the numeral 1 designates an elongated cylindrical body or metal cartridge case about fourteen inches in length, preferably made of seamless or welded tubing having an O. D. of approximately $4\frac{7}{16}$ inches, and of uniform wall thickness of approximately $\frac{1}{16}$ of an inch. Tubing having a longitudinally welded seam has been found to give excellent results and as not being impaired at the seam in the flanging and processing steps.

The cap or base end of the cartridge case or annulus 1 is formed in any suitable way, but preferably by spinning, with an inwardly tapered portion 2 bent on a $\frac{1}{16}$ inch radius at approximately an angle of 45 degrees, the end of which portion is bent again on a $\frac{1}{16}$ inch radius into

2

an axially extending portion having the same wall thickness as the body of the case and an I. D. of $3\frac{3}{8}$ inches and a length of $\frac{1}{8}$ inch concentric with the main body of the case. This bending 5 of the end of the case forms it with the integral compound curved flange 2 and 3 as illustrated.

The base of the cartridge case is made of a disc cut from round bar stock, or it may be a stamping, forging, casting or the like. In any 10 event it is formed on its inner face with an axially extending $\frac{5}{16}$ inch wide groove 5 formed with concentric axial flanges 6 and 7. The inner flange 6 has an O. D. of $3\frac{7}{32}$ inches and is much longer than the outer flange 7 which stands $\frac{1}{16}$ of an 15 inch from the outer face of the base to the tip of the flange, while the inner flange stands $1\frac{7}{32}$ inches from the same face of the base to its tip. The base also has an annular collar or flange 8 and a central inwardly extending boss 9 which is 20 bored or tapped for the fuse cap of the primer charge. The outer face of the outer flange 7 is tapered at an angle of 7 degrees while its inner face has a 45 degree angle. The outer face of flange 6 is perfectly cylindrical and normal to the 25 base, while its inner face at its tip is inclined at an angle of 15 degrees to merge into its transverse end with a $\frac{1}{16}$ inch radius and into base 4 on a $\frac{1}{16}$ inch radius. Thus the base is provided with a groove 5 which is $\frac{1}{16}$ of an inch 30 wider than the wall thickness of the flange end 3 of the case to freely receive such end and to provide for rapid centering and alignment thereof as well as to provide for the subsequent thickening or upsetting of the end within such groove.

35 The method of assembling the base 4 on the case 1, is to insert the latter in a slide fit ring die 40 which in this illustration, has a die cavity terminating in a 20 degree angle bottom 12 to back up the outer flange 7. This ring die is seated 40 in a cavity in the upper end of a hollow stand 13 and is held by a ring retainer plate secured to the stand by screws 15 as shown. When the case 1 is inserted through the ring die 40 and down into the hollow stand, it has a clearance with the 45 bore through the stand as illustrated, and the projectile end of the case is supported upon a spring pad, not shown, in the base of the stand to permit axial movement of the case during assembling and may serve to eject the case later in the usual manner. A male die post 16 is disposed concentric and longitudinally in the hollow stand to removably support the male die 17 on top of the post by means of a screw 18 and within the female die with clearance therebetween for insertion of the case. The upper portion of the male

die 17 is formed with a convex nose swung on a $\frac{1}{2}$ inch radius merging into an annular shoulder 19 arranged a distance below the cavity 12 of the female die so that the cylindrical wall of the female die firmly backs up the cylindrical case during the processing.

The base 4 is then placed upon the case with the flange 3 entered in the groove 5 as shown in Figs. 1 and 4, and with the tip of the inner base flange 6 engaging the convex surface of the male die 17 and the end of flange 3 bottomed in the groove 5. The punch or ram 20 of the press is then lowered to engage the base to move the case down through the ring die 10 and into the stand 13. As the base and case are being forced downwardly by the ram, the tip of the inner flange 6 of the base is first flared outwardly by the male die 17, into engagement with the case 1 below the cavity 12 in the female die 10, as shown to advantage in Fig. 2. As the case is forced farther downwardly into the female die 10, the nose of the male die 17 causes the inner flange to progressively pinch or squeeze more and more of the case against the female die with longitudinal and radial outward pressure. This causes the metal of the case in the area between the inner flange 6 and female die to crowd or flow longitudinally into the flanged portions 2 and 3. This longitudinal displacement of metal causes the flange 3 to upset and increase in wall thickness above that of the original case 1 to pack and completely fill the wider groove 5 in the base.

It will be appreciated that the inner flange 6 of the base has its inner tip surface beveled for coordination with the curvature of the male die so that the flange will be progressively moved with progressively increasing pressure into engagement with the case, to iron this portion of the case longitudinally and against the wall of the female die and against the outer flange 7 which backs up the flanged portion 2 of the case, whereby the displaced metal will be squeezed into and thicken the extremity 3 while portions of the two flanges are being simultaneously pressed toward one another to firmly lock this thickened flange into the base. When the outer flange 7 moves down into the female die cavity 12, it is pressed inwardly to closely engage the flange 2 and densify molecular structure of the flange 7. As the $\frac{1}{2}$ inch radius of the male die 17 bottoms against the $\frac{3}{16}$ radius of the base 4 it will be seen that the base portions of flange 6 engaging the flange portions 2 and 3 will be thinned and compacted firmly against and lock the thickened case flange in its space between the flanges 6 and 7. In the final pressure stage of the press, the shoulder 19 of the male die engages the extreme end of the flange 6 to deform it into a thin annular fin or flange 22 which seals against the shoulder formed in the case and serves as a fill or reinforcement for the end of the thinned portion of the case.

After the dies have bottomed and have formed the joint as shown in Fig. 5, the ram 20 is elevated, and either the spring pressure pad or the male die can be automatically moved upwardly to assist in ejecting the shell. Thereafter, the base 4 is machined down to the dash line 25 shown in Fig. 5 to finish its exterior, or the base may be pre-shaped to final form before being attached to the case.

The grain or fiber of the metal base 4 extends lengthwise of the flanges and is compacted in the outer flange adjacent the flange 2 while the grain of the inner flange 6 is compacted and follows

the contour of the compound bend of the flanges 2 and 3 as best shown by the dot and dash lines in Fig. 5. Any stress imposed upon the joint formed, creates leverage in the vicinity of the two points 23 and 24 at opposite surfaces of the flange to create a compound compression seal. Hydrostatic pressure tests prove the joint invulnerable and show that the cylindrical contour of the case is maintained about $\frac{1}{8}$ of an inch beyond the fin 22 and toward the projectile end of the shell indicating the supreme strength of the joint under tests which are so severe as to actually bow the case outwardly.

While the parts of the cartridge case may be made from any kind of metal, the present invention was devised in order that it could be efficiently made of steel to replace the more expensive one piece drawn brass cases. In this connection, the cylindrical body 1 of the case is preferably made of steel tubing possessing a single longitudinally extending welded seam for effecting economy of materials in the construction of the case. The method of processing the device, and its construction were conformed, to compensate for working of the metal to obviate any danger of impairing or opening the welded stock, so that this less expensive material could be utilized to economize in the manufacture of this essential defense material. The case is made simply in two pieces which are united very rapidly in a manner to provide a case which is more resistant to impact than the former brass cases, and is stronger at the joint than former multiple piece cases. The cases can be rendered rust-proof in various ways, so that they can be stored for indefinite periods or reused, and one efficacious method is to electro-plate the cases with a thin coat of copper when completed.

It will of course be appreciated that the invention is not limited to the production of cartridge cases, but may be employed as a joint of general application between any form of annulus and end closure. It will also be understood that various changes in the size, shape and relation of parts may be resorted to without departing from the spirit of the invention or the scope of the appended claims.

We claim:

1. The method of uniting a metallic annulus with a groove in a metallic base defined between a pair of spaced inner and outer annular flanges, said groove being slightly wider than the wall thickness of said annulus, inserting the annulus into a confining die with its end inserted into said groove, moving said base and annulus axially relative to said die to restrict radial movement of said annulus, moving a male die against said inner flange to force the same radially outward to pinch the annulus against said confining die, and as the base and annulus are moved further to cause the inner flange to progressively iron the metal of said annulus out against said confining die to flow the metal of said annulus axially thereof as the outer flange is moved to engage the confining die to thereby form a continuation of said confining die wall and thereafter exerting radially outward and axial pressure upon said inner flange causing metal of the annulus to flow toward the end thereof to thicken the same in said groove while continuing radial inward and outward pressures upon the outer and inner flanges respectively to lock said thickened portions of said annulus within said groove.

2. The method of uniting a metallic annulus with a groove in a metallic base defined between

the high inner base flange having a straight outerwall and a low outer base flange having an inner wall inclined outwardly away from the inner flange, bending the end of said annulus inwardly into a compound bend with a reduced inclined portion approximating the length of said inclined wall of said outer flange and terminating in an axially extending end, inserting said annulus for limited axial movement in a radial confining die with said reduced axially extending terminal of said annulus positioned in said groove between said inner and outer flanges, moving said base and annulus axially of said die while forming the end of said inner flange outwardly whereby its free edge pinches the annulus below said compound bend against said confining die, continuing the movement of said annulus axially of said die and exerting radial outward pressure on said inner flange to cause the same to be ironed out against the annulus backed up by said confining die, said outer flange being moved axially against said confining die to back up said annulus as said inner flange is progressively squeezed inwardly and axially from its free edge thereby causing the metal of said annulus to progressively flow into the reduced end thereof and to crowd its metal into said groove to increase its wall thickness while said two flanges are forced toward each other against opposite sides of the thickened reduced end of the annulus.

3. The method of mounting a steel annulus with a base consisting of providing a base having a groove wider than the wall thickness of said annulus, inserting the end of said annulus in said groove, exerting radially outward pressure upon that portion of the annulus immediately adjacent the inserted end of the annulus while confining the exterior of said portion of the annulus, and exerting axial pressure on said annulus, said axial and radial pressure serving to thicken said end in said groove above the original wall thick-

ness of the annulus, and concurrently with the exertion of said axial and radial pressure, compressing the walls defining said groove upon the thickened end in the direction of said thickening.
